UNITED STATES PATENT OFFICE.

JACOB HARSEN, OF NEW YORK, N. Y.

TUBE-CLEANER.

1,047,939.

Specification of Letters Patent.

Patented Dec. 24, 1912.

Application filed November 14, 1911. Serial No. 660,254.

To all whom it may concern:

Be it known that I, JACOB HARSEN, citizen of the United States, residing at New York, in the county of New York and State 5 of New York, have invented certain new and useful Improvements in Tube-Cleaners, of which the following is a specification.

This invention relates to tube cleaners, more particularly, it belongs to that class of 10 contrivances designed to loosen and remove scale from the interior of steam boiler tubes, and especially, to that type of cleaners provided with reciprocating scrapers or tools.

The object of this invention is the production of a tube cleaner of the character stated 15 comprising parts having each a certain construction and relation or arrangement with regard to the other parts, whereby it is believed a more effective and convenient appliance results than is ordinarily found on sale by the trade.

The construction and arrangement of parts are illustrated in the accompanying drawings, of which—

25 Figure 1 represents the section lengthwise of a part of a tube with this invention shown therein, also partly in section. Fig. 2 is a transverse section on the indirect broken line $y-y$ of Fig. 1. Fig. 3 is an end 30 view of this invention with the motor removed, looking toward the left hand as indicated by the arrow, and showing the motor shaft in section on line $x-x$ of Fig. 1. Fig. 4 is a view of the under side of one of the 35 chisels, and Fig. 5 is a side view thereof with the roller shown in section.

The same letter is used to refer to the same part throughout the description and drawings.

40 Within the tube A, and attached to steam pipe B by way of which water or steam may be served, is a motor C provided with an encircling extension e movably fitting the tube interiorly and acting as a guide as the 45 motor is moved forward into tube A.

The mouth of the motor casing is threaded as shown and engages the cylinder D. Fitting movably in cylinder D is the rotary cylinder E, provided with the cam 50 groove e and usually formed integrally with the motor shaft F. On the left the cylinder D, relatively the stationary cylinder, is closed by the head plate d and the end f of the motor shaft passes centrally through the 55 head to steady the operation of the motor.

The cylinder D carries a number of chisels G, and each chisel has a block portion provided with guide grooves g that engage the tongues H and h formed on the sides of suitable longitudinal recesses formed usually 60 at equal distances apart in cylinder D. Each chisel G is provided with a roller J constructed and arranged to engage the cam groove in the rotary cylinder E. The driving fluid entering the motor by way of the 65 pipe B, passes out of the motor C into the cylinder D and thence by way of the orifices K and j , the fluid continues through the rotary cylinder and the head d of the stationary cylinder and washes the chippings and 70 other detached particles from the tube A. The recesses in the cylinder D in which the chisels G are located, as will be noted in Fig. 1 are open recesses and extend lengthwise from the left hand edge of the cylinder. The 75 recesses are marked k . When the motor C is put in operation, the rotary cylinder, by reasons of the engagement of the wall of its cam groove e with the rollers J of the chisels, works those chisels rapidly back and 80 forth in contiguity with the interior of tube A, and any accumulated scale is detached. The whole invention is advanced or withdrawn from tube A, or turned therein by 85 suitably manipulating the pipe A.

Having now described this invention, and explained the mode of its operation, what I claim is:—

1. In a tube cleaner, the combination with a member provided with tool-guiding devices, of a plurality of cutting tools engaging said guiding devices, the said guiding devices being constructed to guide the tools lengthwise with respect to said member, a motor, and means actuated by the motor and 90 constructed to reciprocate the tools and to rotate said member at the same time.

2. In a tube cleaner, the combination with a motor, of a member connected with the motor and provided with recesses extending 95 lengthwise parallel with the axis of the said member, cutting tools having portions constructed to movably engage the recesses of said member, the said recesses and tools being provided with guiding tongues and grooves, and means connected with the motor and constructed to reciprocate the 105 tools with respect to said member.

3. In a tube cleaner, the combination with a motor, of a hollow member connected with 110

the motor and provided with recesses extending lengthwise, cutting tools having portions constructed to movably engage the recesses of said member, the said recesses and tools being provided with guiding tongues and grooves, a rotary cylinder located within said member and connected with said motor, said rotary cylinder having a cam groove, and each tool having a projecting

portion constructed and arranged to engage said cam groove.

In testimony whereof I affix my signature in presence of two witnesses.

JACOB HARSEN.
